(57) **CLAIM**

The ornamental design for an adjustable back pad, as shown and described.

DESCRIPTION

FIG. 1 is an upper frontal perspective view of an adjustable back pad of the first embodiment showing the new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is an upper frontal perspective view similar to FIG. 1, showing a second embodiment of the new design; FIG. 9 is a front elevational view thereof; FIG. 10 is a rear elevational view thereof; FIG. 11 is a right side elevational view thereof; FIG. 12 is a left side elevational view thereof; FIG. 13 is a top plan view thereof; and, FIG. 14 is a bottom plan view thereof.

The dash-dash broken lines are for the purpose of illustrating unclaimed subject matter only and form no part of the claimed design. The dash-dot lines are for the purpose of indicating a boundary of the design on a surface and do not indicate an edge.

1 Claim, 10 Drawing Sheets
